FILE SHARPENING MACHINE

Frank N. Moon, Oil City, and Lynn E. Wible, Reno, Pa.
 Substituted for application No. 186,282, September 22, 1950. This application April 1, 1955, Serial No. 498,722

10 Claims. (Cl. 51—58)

This invention relates to file sharpening machines and more particularly to a machine for honing files to a sharp condition.

It is among the objects of the invention to provide an improved file sharpening machine which will individually hone the file teeth or serrations to a sharp condition, which will maintain the cutting edges of the file substantially level, which will effectively hone curved file teeth or serrations, which is power operated, rapid and fully automatic in operation, which hones the file teeth in an oil bath, which has a plurality of easily replaceable honing elements, which is adjustable for different concentricities of curved file teeth, and which is strong and durable in construction, economical to manufacture, and easy to use.

Other objects and advantages will become apparent from a consideration of the following description and the appended claims in conjunction with the accompanying drawings, wherein:

Figure 1 is a top plan view of a file sharpening machine illustrative of the invention, parts being broken away and shown in cross section to better illustrate the construction thereof;

Figure 2 is a side elevational view of the file sharpening machine illustrated in Figure 1, parts being broken away and shown in cross section to better illustrate the construction thereof;

Figure 3 is an end elevational view of the file sharpening machine illustrated in Figures 1 and 2 looking at the right hand end of the machine as illustrated in these figures, parts being broken away and shown in cross section to better illustrate the construction of the machine;

Figure 4 is a transverse cross sectional view on the line 4—4 of Figure 2;

Figure 5 is a longitudinal cross sectional view on the line 5—5 of Figure 2;

Figure 6 is a transverse cross sectional view on the line 6—6 of Figure 2;

Figure 7 is a fragmentary side elevational view on a somewhat enlarged scale with parts broken away and shown in cross section to illustrate the mechanical details of the feed mechanism of the machine;

Figure 8 is a fragmentary cross sectional view on the line 8—8 of Figure 2;

Figure 9 is a perspective view of one component of a hone element holding block constituting an operative component of the machine;

Figure 10 is a perspective view of a leaf spring constituting a component of a holding block assembly;

Figure 11 is a perspective view of a hone element and hone element holding block assembly;

Figure 12 is a perspective view of a plunger constituting an operative component of the feed mechanism; and

Figure 13 is a perspective view of a spring finger also constituting an operative component of the feed mechanism of the machine.

With continued reference to the drawings, the numeral 10 indicates a rectangular base plate of rigid construc-

2

tion and conveniently formed of a plate of iron or steel of suitable thickness, although it may be formed of wood or other suitable material without in any way exceeding the scope of the invention.

5 Two end frame members 11 and 12 are mounted on the base plate and extend upwardly therefrom in spaced apart and substantially parallel relationship to each other and substantially perpendicular to the base plate. The end frame member 11 extends transversely of the base plate near one end of the latter and the end frame member 12 extends transversely of the base plate between the frame member 11 and the other end of the base plate.

A table 13 in the form of a flat, rectangular plate, is mounted on the edges of the end frame members 11 and 12 remote from the base plate 10 and is spaced from and substantially parallel to the base plate. Brackets 14 and 15 are mounted on the table 13 directly above the end frame members 11 and 12 respectively and a pair of spaced apart and substantially parallel guide bars 16 and 17 are carried by the brackets 14 and 15 above and substantially parallel to the table 13.

The brackets are provided with spaced apart apertures and the two guide bars 16 and 17 have at their ends screw threaded reduced portions extending through the apertures in the brackets and receiving nuts 18 to rigidly secure the guide bars to the brackets, these brackets being rigidly secured to the frame end members 11 and 12 by suitable means such as the studs 19.

Two slides 20 and 21 are mounted in spaced apart relationship on the guide bars 16 and 17, each of these slides having spaced apart apertures therein each of which slidably receives a corresponding guide bar. These slides are provided in their edges remote from the table 13 with rectangular notches or recesses and a file supporting bed plate 22 is mounted on the slides 20 and 21.

The file bed plate 22 is a rectangular metal bar of rectangular cross sectional shape having a length and width substantially equal to the length and width of the file to be sharpened on the machine and is rigidly secured to the slides 20 and 21 by suitable means, such as the cap screws 23. The bar 22 is provided with transversely extending grooves of inverted, T-shaped cross section located one near each end of the bar as indicated at 24 and 25. The file 26, of the type to be sharpened by this machine, is provided with apertures extending therethrough, one near each end thereof of which apertures register with the grooves 24 and 25 in the bed plate bar 22. Suitable rectangular nuts are slidably mounted in the wider portions of the grooves 24 and 25 and screws, as indicated at 27 and 28 in Figures 5, are inserted through the apertures in the file and threaded into the nuts received in the wider portions of the grooves to rigidly secure the file to the bed plate.

Since the nuts for the screws 27 and 28 are slidably received in the T-shaped grooves in the bed plate, the file can be adjusted transversely of the bed plate within suitable limits to properly center the file in the machine.

The file 26 is of the type used in smoothing automobile bodies during repair work thereon and has coarse, arcuately curved teeth which extend transversely across the file from one side to the other. The centers of curvature of the file teeth lie on a common line extending longitudinally of the file. In some files this line of centers extends along the mid-width location of the file but, with different files, this line may be displaced to either side of the mid-width location which renders it necessary to provide means for adjustably centering the file relative to the file sharpening machine.

The file supporting bed plate 22 is surrounded by a rectangular oil pan 29 which is secured to the bed plate and extends above the upper surface of the bed plate a distance sufficient to maintain a file mounted on the

bed plate immersed in a bath of oil during the honing operation. The file teeth are thus honed under an oil bath which prevents the cutting edges of the teeth from becoming overheated and also carries away the cuttings or abrasive material so that the honing points or elements do not become clogged.

Four posts 30, 31, 32, and 33 are secured at their lower ends to the rectangular table 13 one near each corner of the table and extend upwardly from the table substantially perpendicular thereto and a tool head, generally indicated at 34, is supported by these posts above the file supporting bed plate 22. Each of the posts is provided near its lower end with an annular collar 35 constituting a stop shoulder resting on the upper surface of the table plate 13 and with a screw threaded portion extending from this collar through a corresponding aperture in the table plate. A nut 36 threaded on the end of the post at the lower side of the table plate rigidly secures each post at its lower end to the table. At a location just above the upper surface of the bed plate 22 each post is provided with a second annular collar 37 and the tool head 34 includes a rectangular bottom plate 38 having apertures therein one near each corner and respectively receiving the posts 30, 31, 32 and 33 above the corresponding stop collars 37. The posts extend above the bottom plate 38 and nuts 39 are threaded one on the upper end of each post. Spring abutment washers 40 surround the posts immediately below the corresponding nuts 39 and coiled compression springs 41 respectively surround the posts between the corresponding abutment washers 40 and the upper surface of the bottom plate 38.

The bottom plate 38 is provided with additional apertures located one near each of the posts 30, 31, 32 and 33, one substantially midway between the posts 30 and 33 and one substantially midway between the posts 31 and 32 and bolts 41' are secured at their lower ends one in each of these additional apertures in the bottom plate 38. These bolts extend upwardly from the bottom plate 38 substantially perpendicular thereto and a top plate 42 is provided with apertures respectively receiving these bolts. Spacer sleeves 43 surround the bolts between the bottom plate 38 and the top plate 42 and nuts 44 threaded on the bolts and bearing against the upper surface of the top plate 42 secure the plates 38 and 42 together in spaced apart and substantially parallel relationship to each other.

Guide blocks 45 of crescent shaped cross section are disposed in the space between the bottom plate 38 and the top plate 42 and are equally spaced apart with their partly cylindrical surfaces disposed perpendicular to the bottom and top plates of the two heads. These guide blocks are secured to the bottom plate 38 by suitable means such as the cap screws 46 and dowels 47 and 48 disposed one at each side of the corresponding cap screw.

These guide blocks are mounted on the bottom plate 38 so that the concave side of one block is opposed to the convex side of the adjacent block and the spaces between adjacent blocks constitute curved guideways, the mean curvature of which corresponds exactly to the curvature of the teeth of the file.

The bottom plate 38 is provided with crescent shaped apertures 49 disposed one between each two adjacent guide blocks 45 for the projection of honing points or elements through the bottom plate 38.

Hollow housings 50 are disposed one between each two adjacent guide blocks 45 for carrying the hone elements and hone holders. Each of these housings is a three part structure including a body portion 51 having a rectangular recess in one side thereof and having its other side exteriorly convex on a partly cylindrical curvature to fit the cylindrically curved concave face of the adjacent guide block 45, a cover 52 which overlies the recess in the body portion 51 and has its face remote from the body portion concavely curved on a partly

cylindrical curvature to fit the partly cylindrical convex face of the adjacent guide block 45. The cover 52 is secured to the body portion 51 by suitable means, such as screws, and a cap 53, particularly illustrated in Figure 9, is mounted on the end of each housing 50 adjacent the upper plate 42.

The cap 53 comprises a plate portion 54 of the same shape as the upper end of the housing 50 and having screw holes 55 therein for the reception of screws which attach the cap to the body portion 51 and cover 52 of the housing. The cap also includes a cylindrical pin 56 projecting upwardly from the upper surface thereof.

When all of the housings 50 are mounted in the spaces between the adjacent guide blocks 45, the pins 56 will be disposed in a row extending longitudinally of the top plate 42 and contacting the undersurface of this plate. The ends of the housings opposite the pins 56 ride on the upper surface of the bottom plate 38 around the apertures 49 in the bottom plate so that the housings are supported in upright position in the tool head for sliding movement transversely of the plates 38 and 42 through the guideways between adjacent guide blocks 45.

Hone element holders 57 are mounted one in each housing 50 and each holder 57 carries a hone element 64 which projects from the holder through the corresponding aperture 49 in the plate 38 into contact with a file 26 supported on the bed plate 22 in the manner indicated above.

Each of the hone holders 57, as particularly illustrated in Figure 11, comprises a rectangular metal block 59 having a beveled end 60 and a rectangular recess 61 in one face thereof opening to the beveled end, and a rectangular cover 62 which fits upon the recessed face of the block 59 and has a beveled end 63 complementary to the beveled end 60 of the block 59. A honing element 64 of rectangular shape and having a beveled end 65 projecting from the beveled end of the holder is mounted in the recess 61 of the block 59 and secured therein by the cover 62. The honing element is secured in the holder against movement under ordinary conditions by disposing a layer of thin sheet material, such as paper, around the portion of the honing element received in the recess 61 or by precoating this portion of the honing element with a coating of material such as a synthetic resin plastic.

The cover is secured to the block 59 by suitable means such as the screws 66 extending through holes in the block and threaded into tapped holes in the cover and the cover 62 is provided at its end remote from the beveled end 63 with an outwardly projecting shoulder 67. The body portion 51 of the housing 50 is provided at its upper end with a shoulder receiving recess 68 and contact of the shoulder 67 with the bottom of this recess provides a limit stop for movement of the holder 57 downwardly relative to the corresponding housing.

A longitudinally curved flat spring 69 is disposed between the inner or undersurface of the housing cap 53 and the adjacent end of the holder 57 to apply a downwardly directed resilient force to the holder and maintain the associated honing element 67 in firm contact with a file being honed.

A rectangular head plate 70 is slidably mounted in the space between the top plate 42 of the tool head and the adjacent ends of the guide blocks 45 and has an elongated slot 73 extending longitudinally thereof and receiving the pins 56 of the housings 50 which carry the hone holders and honing elements. Guide brackets 71 and 72 are secured to the head plate 70 and overlap the respectively opposite ends of the top plate 42 to hold the head plate against longitudinal movement relative to the top plate while permitting sliding movement of the head plate laterally or transversely of the top plate 42.

A bar 74, shorter than the slot 73, is slidably disposed in this slot and has spaced apart apertures respectively receiving the pins 56 to move the housings 50 back and

forth in the guideways between guide blocks 45. The sliding of the bar 74 in slot 73 compensates for the curvature of the guideways.

Arbor pins 75 and 76 project outwardly from the respectively opposite ends of the head plate 70 for a purpose to be presently described.

A pair of standards 77 and 78 are secured to and extend upwardly from the base plate 10 at respectively opposite ends of the base plate and at one side of the table plate 13. An eccentric shaft 80 is journaled at its respectively opposite ends in the standards 77 and 78 at the upper ends of the standards by suitable means, such as the anti-friction ball bearings 81. A third standard 82 is mounted on the base plate at the side of shaft 80 remote from the table plate 13 and has two upwardly extending legs 83 and 84. A main drive shaft 85 is journaled by means of suitable anti-friction bearings 86 and 87 in the legs 83 and 84 at the upper ends of these legs. This main drive shaft 85 has on its end remote from the shaft 80 a belt pulley 88 for receiving a belt by means of which the main drive shaft 85 is drivingly connected to a suitable power plant, such as an electric motor, mounted on the base plate 10.

A beveled pinion gear 90 is mounted on the end of main drive shaft 85 remote from the belt pulley 88 and a beveled pinion gear 90 larger than the pinion 89 is mounted on the shaft 80 and meshes with the pinion 89 to provide a driving connection from the shaft 85 to the shaft 80.

Eccentrics 91 and 92 are mounted on the shaft 80, one at each end of the shaft and at the outer sides of the standards 77 and 78 respectively and connecting rods 93 and 94 connect the eccentrics 91 and 92 to the arbor pins 75 and 76 respectively on the head plate 70. The connecting rod 93 has at one end an aperture which rotatably receives the eccentric 91 and has at its other end an aperture receiving an anti-friction roller bearing mounted on the arbor pin 75. The connecting rod 94 also has at one end an aperture receiving the eccentric 92 and at its other end an aperture receiving an anti-friction ball bearing 95 mounted on the arbor pin 76. The ball bearing is secured on the arbor pin between a shoulder on the latter and nuts 96 threaded onto the screw threaded outer end of the pin. An annular shoulder in the bearing receiving opening in the connecting rod bears against the inner side of the outer race of the bearing 95 and a plate 97 secured to the outer side of the connecting rod has a nut receiving opening therein and a flange surrounding this opening and bearing against the outer side of the outer race of the ball bearing to maintain the corresponding end of the connecting rod against movement relative to the outer race of the ball bearing. The plate 97 is secured to the connecting rod by suitable means such as screws, not illustrated.

The eccentric 92 is provided at its inner end adjacent the standard 78 with an outwardly projecting annular flange providing a stop shoulder for the inner side of the connecting rod 94 and a plate 98 is secured to the outer end of the eccentric by suitable screws 99 and marginally overlaps the connecting rod 94 to hold the connecting rod between itself and the flange 100 on the inner end of the eccentric. The construction of the connecting rod 93 and associated bearing parts is the same as that of the connecting rod 94 and associated bearing parts, as described above.

With this arrangement, when the eccentric shaft 80 is driven by the main drive shaft 85 through the gears 89 and 90, the eccentrics 91 and 92 and the connecting rods 93 and 94 will impart a reciprocatory movement to the head plate 70 in a lateral direction or transversely of the top plate 42 of the tool head. This will move the housings 50 back and forth through the curved guideways between the adjacent guide blocks 45 and this movement of the housings 50 will move the holders 57 and honing elements 64 back and forth in arcuately curved

paths transversely of a file supported on the bed plate 22. The shape of the guide blocks 45 is such that the beveled ends of the honing elements 64 will exactly follow the curvature of the file teeth and the guide blocks 45, the housings 50, the holders 57 and honing elements 64 are so dimensioned that the beveled ends of the honing elements are successively spaced apart the same distance which distance is equal to a predetermined number of successive file teeth.

In the arrangement illustrated there are seven honing elements. If these elements are spaced apart a distance of seven successive file teeth and the file has forty-nine or fifty teeth on one side, all of the file teeth can be honed in seven successive honing operations.

A bearing block 105 is mounted on the base plate 10 adjacent the inner side of the frame end member 11 and substantially parallel to the latter. This bearing block has two spaced apart bearing receiving apertures therein in each of which is mounted an anti-friction ball bearing 106.

A similar bearing block 107 is mounted on the base plate 10 spaced from the side of the end frame member 12 remote from the member 11 and having spaced apart apertures therein receiving anti-friction ball bearings, as indicated at 108.

Two cam shafts 109 and 110 are journaled in the anti-friction bearings carried by the bearing blocks 105 and 107 and are disposed in spaced apart and substantially parallel relationship between the base plate 10 and the table plate 13 and substantially parallel to both of these plates.

Two substantially cylindrical cams 111 and 112 are mounted on the shaft 109 one near the bearing block 105 and one near the frame end member 12 and two similar cams 113 and 114 are mounted on the shaft 110 in corresponding positions. The main portion of the peripheral surface of each cam is substantially cylindrical but the cylindrical peripheral surface is interrupted by a single cam lobe 115 which projects outwardly from the cylindrical surface and has flat side faces which mutually converge from the cylindrical surface to the point or peak of the lobe and are inclined at different angles to a radius extending from the axis of rotation of the cam through the peak of the cam lobe, the face at the back side of such radius in the direction of rotation of the cam being steeper than the face at the front side of the radius.

A worm wheel 116 is mounted on the shaft 109 between the frame end member 12 and the bearing block 107 and a similar worm wheel 117 is mounted on the cam shaft 110 in the corresponding locations.

Bearing brackets 118 and 119 are mounted on the base plate 10 at the opposite ends of the space between the frame end member 12 and the bearing block 107 and these bearing brackets are provided near their upper ends with openings receiving anti-friction ball bearings 120 and 121 respectively. A worm shaft 122 is journaled in the bearings 120 and 121 and is disposed immediately above the worm gears 116 and 117 and at right angles to the cam shafts 109 and 110.

Worms 123 and 124 are provided on the shaft 122 and mesh with the worm gears 116 and 117 respectively, the arrangement being such that the worms and worm gears drive the shafts 109 and 110 at the same speed in respectively opposite directions.

Bearing projections 125 and 126 are mounted on and project perpendicularly outward from the standards 78 one near the eccentric shaft 80 and the other between the worm shaft 122 and the base plate 10. These extensions are provided with openings receiving anti-friction ball bearings 127 and 128 respectively and a vertically disposed shaft 129 is journaled near its opposite ends in these ball bearings. A beveled gear 130 is secured on the upper end of the vertical shaft 129 and a beveled gear 131 materially smaller than the gear 130 is mounted

on the shaft 80 and meshes with the gear 130 to drive the vertical shaft 129 from the eccentric shaft 80.

A beveled gear 132 is secured on the end of the worm shaft 122 adjacent the vertically disposed shaft 129 and a beveled gear 133 materially smaller than the gear 132 is mounted on the shaft 129 and meshes with the gear 132 to drive the worm shaft 122 at a speed greatly reduced from the speed of the eccentric shaft 80. The worm and worm gear driving connections between the worm shaft 122 and the cam shafts 109 and 110 further reduces the rotational speed of the cam shafts so that the eccentric shaft 80 makes a large number of revolutions for each revolution of each of the cam shafts.

Four lifts or tappets 135, 136, 137 and 138, in the form of cylindrical pins, are slidably mounted in corresponding bearing bushings 139 respectively received in openings or apertures provided in the table plate 13 one above each of the cams 111, 112, 113 and 114 so that the lower end of each tappet rests on a corresponding cam. At the upper ends the tappets have reduced portions extending through corresponding apertures provided in the bottom plate 38 of the toolhead and this bottom plate is rigidly secured to the tappets by nuts 140 threaded onto the reduced end portions of the tappets and bearing on the upper surface of the bottom plate 38.

The cams are set so that the cam lobes simultaneously contact the lower ends of all of the tappets to raise the tool head when the cam lobes are brought under the tappets.

The operation of the mechanism is such that a predetermined number of honing strokes will be given to the honing elements 64 and the tool head will then be raised by the cams and tappets to lift all of the honing elements above the work surface of a file being honed so that the file can be moved longitudinally to present new teeth to the honing elements. Suitable feeding means are operative while the honing elements are lifted from the file to feed the file one tooth in its feeding direction to bring a new tooth into engagement with each of the honing elements. The file is thus periodically fed past the honing elements, a predetermined number of honing strokes being given to the teeth between these feeding movements and the honing elements being lifted entirely clear of the file while the feeding of the file is being accomplished.

The springs 41 on the posts 30, 31, 32 and 33 resiliently urge the tool head downwardly at all times, maintaining the tappets or lifts 135, 136, 137 and 138 in firm contact with the associated cams 111, 113, 114 and 112 and return the honing elements 64 to honing engagement with the file after the tool head has been lifted by the cam lobes for a feeding movement of the file.

A lever 41 is disposed at the outer side of the end frame member 12 and is pivotally connected intermediate its length by a pivot pin 142 to a bracket 143 mounted on the member 12 at the corresponding end of the table plate 13. An aperture 144 is provided in the frame member 12 opposite the cam 112 and a screw threaded counterbore 145 is provided in the side of the member 12 adjacent the cam. A hollow cylindrical nut 146 is threaded into the counterbore and a plunger 147 extends through this nut and through the aperture 144 in the member 12 and contacts at one end an abutment 148 carried by the lever 141 at the lower end of the latter. An extension or lobe 149 is provided on the face of the cam 112 facing the member 12 and this extension contacts the adjacent end of the plunger 147 when the cam lobes contact the tappets to raise the tool head. An annular collar 150 is provided on the plunger 147 within the nut 146 and a compression spring 151 surrounds the plunger between this collar and the end of the counterbore 145 to maintain the plunger in contact with the adjacent face of the cam 112.

A spring finger 152, as particularly illustrated in Figure 13, is secured at one end to the upper end of the lever 141 and overlies the adjacent end portion of a file 26 se-

cured on the bed plate 22. The finger 152 is a flat leaf spring having near one end an aperture 153 which receives a screw 154 which attaches this end of the spring finger to the upper end of the lever 141. The other or distal end of the finger is bent downwardly, as indicated at 155 and the end is arcuately biased to fit the curved teeth or serrations of the file. With this arrangement, when the projection 149 strikes the adjacent end of the plunger 147 the lever 141 is swung about the pivot pin 142 and forces the spring finger 152 in a direction to move the file one tooth in a direction away from the lever. As explained above, this occurs while the honing elements 64 are lifted from the file.

A coiled tension spring 156 is secured at one end to a pin 157 mounted in an aperture in the slide 20 between the slide bars 16 and 17 and extends through an aperture 158 provided in the slide 21. At its other end this spring is connected by a pin 159 to the bracket 15 supporting the guide rods and acts to resiliently urge the bed plate 22 and a file mounted thereon toward the lever 141. This return movement of the file is stopped by a second spring finger 160 mounted at one end on the upper end of an extension 161 projecting upwardly from the bracket 143.

25 The pin 157 is extended from the slide 20 toward the adjacent ends of the slide bars 116 and 117 and a micro switch 162 is mounted on a bracket 163 secured to the frame end member 11, the micro switch being positioned for operation by the adjacent end of the pin 157 when 30 the file has been fed to its limiting position. The micro switch 162 is connected into the circuit of the machine driving motor in a manner to automatically stop the operation of the machine when the honing of the file has been completed.

35 A block 164 is mounted on the end of the bed plate 22 adjacent the feed lever 141 and is provided in its upper end with serrations or teeth which continue the file teeth somewhat beyond the adjacent end of the file. This permits the corresponding end of the file to be moved 40 somewhat past the hone element nearest the feed lever 141 so that, if the file has an uneven number of teeth all of the teeth can be subjected to the honing operation.

45 From the above description it will be noted that the machine is fully automatic in operation and will give each tooth of a file a predetermined number of honing strokes and will then feed the file forwardly one tooth to bring new teeth into engagement with the honing elements, the feed progressing step by step and one tooth at a time. When the honing of one side of the file is completed, the 50 screws securing the file to the bed plate are removed and the file is slipped out of the machine at the end of the machine remote from the feed lever and is turned over and replaced on the bed plate, the spring fingers 160 and 152 being manually raised while the corresponding end portion of the file is inserted thereunder.

55 The curved file teeth are effectively honed from one end to the other and are honed only on their sharpened edges so that the edges of the teeth or serrations are maintained in a level or even condition and the file is not rapidly worn away as is the case with existing file sharpened methods.

This application is a substitute of application Serial No. 186,282, filed September 22, 1950, now abandoned.

Having thus described the invention, what is claimed 60 as new is:

65 1. A file honing machine comprising a base, upright frame elements supported on said base, spaced apart guide bars mounted on said frame elements, a file supporting bed plate slidably mounted on said guide bars for longitudinal movement, a tool head mounted on said frame elements above said bed plate for movement toward and away from the latter, guide blocks having cylindrically curved faces mounted in said tool head in spaced apart relationship to provide therebetween curved guideways corresponding to the curvature of the teeth of a file to

be honed, transversely curved housings slidably mounted one in each space between adjacent guide blocks, hone element holders mounted one in each housing, hone elements carried one by each holder and projecting from the end of the latter adjacent said bed plate for operative engagement with a file supported on said bed plate, pins provided one on each of said housings at the end thereof remote from the corresponding hone element, a head plate having an elongated slot therein receiving all of said pins and mounted on said tool head for sliding movements transversely of the latter, a bar disposed in the slot of said head plate and having apertures therein respectively receiving said pins, a shaft journaled on said frame elements and disposed substantially parallel to said head plate, eccentrics on said shaft, connecting rods connecting said eccentrics to said head plate at the opposite ends of the latter for moving said housings back and forth in said curved guideways, said housings having a freedom of movement in said curved guideways substantially equal to the width of a file to be sharpened, drive means mounted on said frame elements and drivingly connected with said shaft, cam shafts journaled in said frame elements below and substantially parallel to said bed plate, single lobe cams on said cam shafts, tappets extending one from each cam to said tool head for lifting the latter when said tappets are engaged by the cam lobes, cam shaft driving means connected between said shaft driving means and said cam shafts rotating said cam shafts at a speed materially less than the rotational speed of the first mentioned shaft, a lever pivotally mounted intermediate its length on one of said frame elements, a projection on one of said cams engaging said lever to impart periodic movement to the latter, a first spring finger carried by said lever for engaging a file mounted on said bed plate to move said bed plate and a file mounted thereon in a file feeding direction upon movement of said lever, an expansion spring connected between said frame elements and said bed plate resiliently urging said bed plate and a file carried thereon in the opposite direction, and a second spring finger mounted on said one frame element for engaging a bed plate carried file to hold such file and bed plate against return movement by said expansion spring when the bed plate has been moved in a file feeding direction by said first spring finger.

2. A file honing machine comprising a frame structure including a pair of substantially parallel slide bars, a file supporting bed plate slidably mounted on said slide bars for longitudinal movement relative to said frame structure, a tool head mounted on said frame structure and including spaced apart guide blocks having transversely curved adjacent faces providing curved guideways therebetween, transversely curved housings disposed in said guideways for reciprocatory movement therein with their curved sides in contact with the transversely curved faces of said guide blocks, honing elements carried one by each housing and depending from said housings to engage a file supported on said bed plate, power operated means connected to said housings for imparting reciprocatory movements thereto to move said honing elements transversely of a file supported on said bed plate, cam means driven by said power operated means for periodically lifting said tool head to move said honing elements away from a file supported on said bed plate, and feed means mounted on said frame structure and operated by said cam means to periodically move said bed plate and a file supported thereon in a file feeding direction while said tool head is lifted.

3. A file honing machine comprising a frame structure, a file supporting bed plate slidably mounted on said frame structure for longitudinal movement relative to the frame structure, a tool head supported on said frame structure at one side of said bed plate and including spaced apart guide blocks having transversely curved adjacent faces providing curved guideways therebetween, transversely curved housings disposed one in each guideway for re-

ciprocatory movement therein with their curved sides in contact with the transversely curved faces of said guide blocks, honing elements carried one by each housing and projecting from said housings toward said bed plate, spring means acting between said frame structure and said tool head resiliently urging said honing elements toward said bed plate, power operated means supported on said frame structure and connected to said housings for imparting reciprocatory movement to the latter, cam means operated by said power operated means and acting between said frame structure and said tool head for periodically moving said honing elements away from said plate against the force of said spring means, and feed means mounted on said frame structure adjacent said bed plate and operated by said cam means to engage a file supported on said bed plate and move said bed plate and a file supported thereon one file tooth at a time during the intervals in which said honing elements are moved away from said bed plate.

4. A file honing machine comprising a frame structure, a file supporting bed plate slidably mounted on said frame structure for longitudinal movement relative to the frame structure, a tool head supported on said frame structure at one side of said bed plate and including spaced apart guide blocks having transversely curved adjacent faces providing curved guideways therebetween, transversely curved housings disposed one in each guideway for reciprocatory movement therein with their curved sides in contact with the transversely curved faces of said guide blocks, honing elements carried one by each housing and projecting from said housings toward said bed plate, spring means acting between said frame structure and said tool head resiliently urging said honing elements toward said bed plate, power operated means supported on said frame structure and connected to said housings for imparting reciprocatory movement to the latter, cam means operated by said power operated means and acting between said frame structure and said tool head for periodically moving said honing elements away from said plate against the force of said spring means, feed means mounted on said frame structure adjacent said bed plate and operated by said cam means to engage a file supported on said bed plate and move said bed plate and a file supported thereon one file tooth at a time during the intervals in which said honing elements are moved away from said bed plate, and a pan mounted on said bed plate and projecting from the side thereof adjacent said honing elements to maintain a file mounted on said side of said bed plate immersed in a liquid bath.

5. A file honing machine comprising a frame structure, a file supporting bed plate slidably mounted on said frame structure for longitudinal movement relative to the frame structure, a tool head supported on said structure at one side of said bed plate and including spaced apart guide blocks having transversely curved adjacent faces providing curved guideways therebetween, transversely curved housings disposed one in each guideway for reciprocatory movement therein with their curved sides in contact with the transversely curved faces of said guide blocks, honing elements carried one by each housing and projecting from said housings toward said bed plate, spring means acting between said frame structure and said tool head resiliently urging said honing elements toward said bed plate, power operated means supported on said frame structure and connected to said housings for imparting reciprocatory movement to the latter, cam means operated by said power operated means and acting between said frame structure and said tool head for periodically moving said honing elements away from said plate against the force of said spring means, feed means mounted on said frame structure adjacent said bed plate and operated by said cam means to engage a file supported on said bed plate and move said bed plate and a file supported thereon one file tooth at a time during the intervals in which said honing elements are moved away from said bed plate,

a spring connected between said frame structure and said bed plate resiliently urging the latter in a direction opposite to said file feeding direction, and a resilient finger mounted on said frame for engaging a file supported on said bed plate and holding said bed plate and a file supported thereon at the positions to which they are moved by said feed means.

6. A file honing machine comprising a frame structure, a file supporting bed plate slidably mounted on said frame structure for longitudinal movement relative to the frame structure, a tool head supported on said structure at one side of said bed plate and including spaced apart guide blocks having transversely curved adjacent faces providing curved guideways therebetween, transversely curved housings disposed one in each guideway for reciprocatory movement therein with their curved sides in contact with the transversely curved faces of said guide blocks, honing elements carried one by each housing and projecting from said housings toward said bed plate, spring means acting between said frame structure and said tool head resiliently urging said honing elements toward said bed plate, power operated means supported on said frame structure and connected to said housings for imparting reciprocatory movement to the latter, cam means operated by said power operated means and acting between said frame structure and said tool head for periodically moving said honing elements away from said plate against the force of said spring means, and feed means mounted on said frame structure adjacent said bed plate and operated by said cam means to engage a file supported on said bed plate and move said bed plate and a file supported thereon one file tooth at a time during the intervals in which said honing elements are moved away from said bed plate, said power operated means being effective to impart a predetermined number of reciprocatory movements to said honing element housings between successive operations of said cam means to move said honing elements away from said bed plate.

7. In a file honing machine, a tool head including spaced apart guide blocks having cylindrical curved opposing faces providing curved guideways therebetween, hollow housings disposed one in each guideway for reciprocatory movement therein and having cylindrically curved faces slidably engaging the cylindrically curved faces of adjacent guide blocks, honing element holders disposed one in each housing and projecting at one end from one end of the latter, and honing elements mounted one in each holder and projecting from said one end of the latter.

8. In a file honing machine, a tool head including spaced apart guide blocks having cylindrically curved opposing faces providing curved guideways therebetween, hollow housings disposed one in each guideway for reciprocatory movement therein and having cylindrically curved faces slidably engaging the cylindrically curved faces of adjacent guide blocks, honing element holders disposed one in each housing and projecting at one end from one end of the latter, honing elements mounted one in each holder and projecting from said one end of the latter, springs disposed one in each housing and acting between the housings and the associated holders to resiliently urge said holders outwardly of the corresponding housings, and stop shoulders on said housings and said holders limiting movement of said holders outwardly of the corresponding housings.

9. A file honing machine comprising a frame structure, a file supporting bed plate slidably mounted on said frame structure for longitudinal movement relative to the frame structure, a tool head supported on said frame structure at one side of said bed plate and including spaced apart guide blocks having transversely curved adjacent faces providing curved guideways therebetween, transversely curved housings disposed one in each guideway for reciprocatory movement therein with their curved sides in contact with the transversely curved faces of said guide

blocks, honing elements carried one by each housing and projecting from said housings toward said bed plate, spring means acting between said frame structure and said tool head resiliently urging said honing elements toward said bed plate, power operated means supported on said frame structure and connected to said housings for imparting reciprocatory movement to the latter, cam means operated by said power operated means and acting between said frame structure and said tool head for periodically moving said honing elements away from said plate against the force of said spring means, and feed means mounted on said frame structure adjacent said bed plate and operated by said cam means to engage a file supported on said bed plate and move said bed plate and a file supported thereon one file tooth at a time during the intervals in which said honing elements are moved away from said bed plate, said power operated means including a shaft journaled on said frame structure, eccentrics on said shaft at spaced apart locations therealong, a head plate engaging said housings, and connecting rods connecting said eccentrics to said head plate to impart lateral reciprocatory movement to the latter.

10. A file honing machine comprising a frame structure, a file supporting bed plate slidably mounted on said frame structure for longitudinal movement relative to the frame structure, a tool head supported on said frame structure at one side of said bed plate and including spaced apart guide blocks having transversely curved adjacent faces providing curved guideways therebetween, transversely curved housings disposed one in each guideway for reciprocatory movement therein with their curved sides in contact with the transversely curved faces of said guide blocks, honing elements carried one by each housing and projecting from said housings toward said bed plate, spring means acting between said frame structure and said tool head resiliently urging said honing elements toward said bed plate, power operated means supported on said frame structure and connected to said housings for imparting reciprocatory movement to the latter, cam means operated by said power operated means and acting between said frame structure and said tool head for periodically moving said honing elements away from said plate against the force of said spring means, and feed means mounted on said frame structure adjacent said bed plate and operated by said cam means to engage a file supported on said bed plate and move said bed plate and a file supported thereon one file tooth at a time during the intervals in which said honing elements are moved away from said bed plate, said cam means including a pair of substantially parallel cam shafts journaled on said frame structure, single lobe cams on said cam shafts at spaced apart locations therealong, tappets slidably mounted in said frame structure and each contacting a corresponding cam at one end and secured at its other end to said tool head, worm gears secured one on each cam shaft at corresponding ends of said cam shafts, a worm shaft journaled in said frame structure and disposed substantially at right angles to said cam shafts, and worms on said worm shaft meshing respectively with said worm gears.
